SAFETY RAZOR ACCESSORY

Sidney H. Benjamin, Milwaukee, Wis.

Application May 4, 1939, Serial No. 271,701

9 Claims. (Cl. 206—16)

My invention relates to safety razors and refers particularly to unitary constructions of some of the elements of safety razor blade accessories.

5 One of the objects of my invention is a unitary construction of a safety razor cap and guard, a safety razor blade carrier, and blades therein, said elements being so maintained as not to be accidentally disassembled under ordinary handling and being capable of being readily disassembled if desired.

Another object of my invention is such a unitary construction as is capable of insertion within a recess within the handle of a safety 15 razor, which can be readily inserted into and removed from such handle recess without disassembling the elements of the unitary construction and which will not become so disassembled while within said recess during the handling of 20 said handle.

Another object of my invention is a unitary construction of a safety razor cap, a safety razor guard, a safety razor blade carrier and blades therein in which these elements are so removably positioned with respect to each other that when so assembled they are maintained in practically immovable relationship with respect to 25 each other.

Another object of my invention is a unitary 30 construction of a safety razor cap, a safety razor guard, and a safety razor blade carrier and blades therein, so removably assembled that when so assembled the said safety razor blade carrier is maintained in immovable horizontal and vertical position with respect to said cap and guard.

While these are the specific objects of my invention, I do not limit myself to such applications of the devices of my invention.

I refer, therefore, to this specific use of the 40 devices of my invention.

Attempts have been made to produce a safety razor of such construction that the entire razor head, including the cap and the guard, with or without a positioned blade, and a blade carrier 45 may be inserted within a recess within the handle, the advantages of such a construction being generally recognized.

The chief difficulty that has been met in producing a safety razor of this construction has 50 been the inability to prevent the various elements from moving with respect to each other while thus inserted in the handle recess.

It is evident that if the cap and guard are not immovably connected, the separation of 55 these elements will allow a blade carried between

them to contact the inner face of the handle recess thus dulling and injuring it and making it unfit for further shaving operations, and hence the cap and the guard must be maintained from vertical, horizontal, and rotatable movement 5 with respect to each other, that is, they must be of an immovable unitary construction with respect to each other.

A blade carrier must be of such a construction that it be adapted to maintain a plurality 10 of wrapped or unwrapped blades while allowing of their removal for use.

It is evident, therefore, that means must be employed to prevent the accidental removal of the blades from the blade carrier during the 15 handling of the handle, in order to prevent them from being injured by contact with the recess wall.

It is further evident that if these several elements of a safety razor and blades become 20 disengaged, or are not connected they will move around within the recess and hence will be subject to damage.

It is to be noted from the above that the only 25 solution of the difficulties thus presented is a unitary construction of the cap, guard, inserted blade and a blade carrier as will prevent any vertical, horizontal, rotary or other movement of these elements with respect to each other under ordinary usage and especially while inserted 30 within a recess within the handle.

My invention overcomes all of the above, and other, difficulties and presents a unitary construction capable of being inserted within a recess within a safety blade handle and which are 35 so removably attached to each other that they will remain in stationary positions with respect to each other during ordinary handling of the razor handle within which they are positioned, while allowing of their proper disengagement 40 when desired.

In the accompanying drawings I illustrate modified forms of the devices of my invention, but I wish to be understood that I do not limit myself to these particular forms of construction 45 as it is evident that variations and changes may be made therein without going beyond the scope of my invention.

In the modified forms of devices of my invention shown in the accompanying drawings, similar parts are designated by similar numerals.

Figure 1 is a side view, partly in section, of one form of a device of my invention, attached to a razor handle.

Figure 2 is an enlarged top plan perspective view of the blade carrier of Figure 1.

Figure 3 is an enlarged top plan view of the guard of Figure 1.

5 Figure 4 is an enlarged bottom plan view of the cap of Figure 1.

Figure 5 is an enlarged plan view of the assembled cap, guard and blade carrier of Figure 1.

10 Figure 6 is an enlarged section through the line 6—6 of Figure 5.

Figure 7 is an enlarged vertical section of the handle of Figure 1 containing the assembled elements.

15 Figure 8 is an enlarged section through the line 8—8 of Figure 7.

Figure 9 is an exploded side view, partly in section of a modified form of my device and of a safety razor handle.

20 Figure 10 is an enlarged perspective view of the blade carrier of Figure 9.

Figure 11 is a plan view of the assembled cap, guard and blade carrier of Figure 9.

25 Figure 12 is a vertical section through a modified form of a device of my invention.

25 Figure 13 is a perspective of the blade carrier of Figure 15.

Figure 14 is a plan view of the cap of Figures 12 and 15.

30 Figure 15 is a vertical section through a modified form of a device of my invention.

Figure 16 is a plan view of the blade clip of Figure 12.

35 Figure 17 is a vertical section through a modified form of a device of my invention.

40 The particular form of a device of my invention disclosed in Figures 1 to 8 comprises a safety razor cap having the longitudinal elongated element 20 and the two dependent end lug members 21 and 21, the terminal inner faces of which are flared slightly inwardly forming the attaching members 22 and 22. The under side of the cap has a longitudinally positioned elongated recess 23 extending between the end lugs 21 and 21. A threaded stud 24 extends outwardly from the central portion of the recess 23 and is adapted 45 to attach the cap, a blade and a later described guard member to a handle 25.

45 A further element of this form of a device of my invention is a guard element comprising the longitudinally elongated member 26 having a plurality of spaced teeth or prongs 27, 27, 27 on each side thereof and a plurality of extended lugs 28, 28, 28 adapted to extend through a corresponding plurality of openings in a later described razor blade and into the recess 23 of the cap. The guard has also an opening 29, so positioned as to allow the stud 24 of the cap to extend therethrough. The guard fits snugly between the end lugs 21, 21 of the cap.

60 In the employment of my device for shaving purposes, a razor blade 30 having a plurality of openings 31, 31, 31 to allow of the passage of the lugs 28, 28, 28 of the guard therethrough, is positioned between the guard and the cap as shown.

65 A further element of this form of the device of my invention comprises a blade carrier comprising a bottom member 32, the end member 33 and the two side members 34, 34 which are 70 bent inwardly toward each other forming the two spaced top members 35, 35. The bottom member 32 has an opening 36 adapted to receive the stud 24 of the cap.

The blade carrier is of such length that it 75 can be forcibly passed downwardly between the

lugs elements 22, 22 of the cap and when so positioned is frictionally maintained between the lugs 21, 21 of the cap and thus prevented from accidental removal therefrom.

5 The upper portion 37 of the handle 25 is extended into a conical or pyramidal form and has an internally threaded opening 38 to receive the stud 24 of the cap.

The blade carrier is adapted to receive a plurality of wrapped or unwrapped blades 30, 30. 10

The unitary construction of this form of my device comprises a cap having extended end lugs and a centrally positioned extended threaded lug, a toothed guard positioned between the end lugs of the cap with the threaded lug of the cap extending through a hole within said guard and a blade carrier, with or without blades, positioned upon the guard and between the end lugs of the cap, said blade carrier being frictionally maintained in place and thus holding 15 the cap, the guard and the blade carrier into a unitary construction.

It is evident that a blade may or may not be positioned between the cap and the guard in this unitary construction. 25

One useful application of this unitary construction is shown in the drawings in which this construction is inserted within a recess 35A of the handle 25, the open end of which has the removable closure 36A. 30

While in Figures 1 to 8 I have disclosed and explained a form of my device in which the cap has a threaded lug capable of being threaded to the handle by means of an internally threaded recess in the latter, it is evident that this particular form of construction of the cap and handle is not necessary in the formation of my unitary construction, and that the exteriorly threaded lug may be carried by the handle and the interiorly threaded recess may be in a 35 portion of the cap.

This construction is shown in the form of my device as illustrated in Figures 9, 10 and 11.

In this form the cap 26 has an internally threaded recess 38A and the handle 25 has an 40 extended exteriorly threaded stud 24A capable of being threaded within the recess 36.

As the opening 36 in the blade carrier in the first described form of my device was adapted for receiving the stud 24 of the cap which extended through the guard and the blades in the carrier, and as the threaded stud of this modified form does not extend through the guard, the extended connecting lug 39 being a part of the handle 25, it is evident that in this form of my device, it is not necessary for the bottom of the blade carrier to have an opening therethrough. 50

In the modified form of my device illustrated in Figures 13, 14 and 15, the cap, the guard and the handle are similar to those shown in Figures 1 to 8 with the exception of the means for producing a unitary construction. 60

In this form of my construction the blade carrier comprises a bottom member 40, the end member 41, and the side members 42, 42. The central portions of the side members 42, 42 are bent inwardly toward each other forming the two spaced top members 43, 43. The two end portions of each side member 42 are bent to form a somewhat curved resilient clasping members 70 44, 44. These clasps are of such form and construction, that when the elements of my device are in the formation of a unitary construction they extend around and beneath the end tooth or teeth of the guard, thus resiliently removably 75

connecting the blade carrier to the guard, and as the guard is frictionally attached to the cap, the elements are maintained in removable unitary construction by both resilient and frictional means.

In the modified form of a device of my invention illustrated in Figures 12, 14 and 16 the cap, guard and handle are similar to those shown in Figures 9, 10 and 11, the exteriorly threaded stud 10 being upon the handle and hence the blade carrier does not require an opening in the bottom thereof, and the unitary construction is similar to that described above.

In the modified form of a device of my invention shown in Figure 17, the clasping members 15 44, 44 of the device shown in Figure 15 are extended into the clasping members 45, 45 which extend around the outer edge of the cap.

It is evident that my invention is not limited 20 to double edge blades as shown and described, and that it is equally applicable to single edge blades.

It is also evident that my invention is not limited 25 to the particular form or function of the cap and guard or to any particular means for maintaining the blade in fixed position for purposes of shaving.

It will thus be seen that my invention presents 30 a unitary construction of a safety razor cap, a safety razor guard, a safety razor blade carrier, and blades therein so arranged that they are practically immovably attached to each other when assembled in the unitary construction, such attachment preventing the elements from vertical, horizontal or revoluble movement with respect 35 to each other, while the elements may be readily removed from each other if desired.

By "unitary construction" in my specification and claims I mean such an assembly of the elements as will maintain them in fixed relationship 40 to each other during its ordinary handling and storage, while the construction, however, will allow the ready disassemblage of the elements when desired.

45 I do not limit myself to the particular size, shape, number, arrangement, or material of parts as specifically shown and described as these are given simply as a means for clearly describing the devices of my invention.

46 What I claim is:

1. A mercantile unit comprising a safety blade carrier adapted to carry a plurality of stacked blades therein, a safety razor cap, a safety razor guard, said elements being longitudinally superimposed upon each other, and means fixedly carried by one of said elements co-operating with another of said elements removably clamping all of said elements into a unitary construction in which all of said elements are prevented from vertical, horizontal and revoluble movement with respect to each other.

2. A mercantile unit comprising a safety blade carrier adapted to carry a plurality of stacked blades therein, a safety razor cap, a safety razor guard, said elements being longitudinally superimposed upon each other, and means fixedly carried by said cap co-operating with another of said elements removably clamping all of said elements into a unitary construction in which all 50 of said elements are prevented from vertical, horizontal and revoluble movement with respect to each other.

3. A mercantile unit comprising a safety blade carrier adapted to carry a plurality of stacked blades therein, a safety razor cap, a safety razor

guard, said elements being longitudinally superimposed upon each other, and means fixedly carried by said guard co-operating with another of said elements removably clamping all of said elements into a unitary construction in which all of said elements are prevented from vertical, horizontal and revoluble movement with respect to each other.

4. A mercantile unit comprising a safety blade carrier adapted to carry a plurality of stacked blades therein, a safety razor cap, a safety razor guard, said elements being longitudinally superimposed upon each other, and means fixedly carried by said safety blade carrier co-operating with another of said elements removably clamping all of said elements into a unitary construction in which all of said elements are prevented from vertical, horizontal and revoluble movement with respect to each other.

5. A mercantile unit comprising a safety blade carrier having stacked blades therein, a safety razor cap, a safety razor guard, said elements being longitudinally superimposed upon each other, and means fixedly carried by one of said elements co-operating with another of said elements removably clamping all of said elements into a unitary construction in which all of said elements are prevented from vertical, horizontal and revoluble movement with respect to each other.

6. A mercantile unit comprising a safety blade carrier having stacked blades therein, a safety razor cap, a safety razor guard, said elements being longitudinally superimposed upon each other, and means fixedly carried by said cap co-operating with another of said elements removably clamping all of said elements into a unitary construction in which all of said elements are prevented from vertical, horizontal and revoluble movement with respect to each other.

7. A mercantile unit comprising a safety blade carrier having stacked blades therein, a safety razor cap, a safety razor guard, said elements being longitudinally superimposed upon each other, and means fixedly carried by said guard co-operating with another of said elements removably clamping all of said elements into a unitary construction in which all of said elements are prevented from vertical, horizontal and revoluble movement with respect to each other.

8. A mercantile unit comprising a safety blade carrier having stacked blades therein, a safety razor cap, a safety razor guard, said elements being longitudinally superimposed upon each other, and means fixedly carried by said blade carrier co-operating with another of said elements removably clamping all of said elements into a unitary construction in which all of said elements are prevented from vertical, horizontal and revoluble movement with respect to each other.

9. A mercantile unit comprising a safety blade carrier adapted to carry a plurality of stacked blades therein, a safety razor cap, a safety razor guard, said elements being longitudinally superimposed upon each other with said guard positioned between said cap and said blade carrier, and means fixedly carried by one of said exteriorly positioned elements co-operating with the other of said exteriorly positioned elements removably clamping all of said elements into a unitary construction in which all of said elements are prevented from vertical, horizontal and revoluble movement with respect to each other.
